UNITED STATES PATENT OFFICE.

JESSE A. B. SMITH, OF STAMFORD, CONNECTICUT, ASSIGNOR TO UNDERWOOD TYPE-
WRITER COMPANY, OF NEW YORK, N. Y., A CORPORATION OF DELAWARE.

TYPEWRITING MACHINE.

Application filed November 10, 1922. Serial No. 599,985.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and more particularly to the provision in a typewriting machine of means for positioning and feeding a pack of small slips at one of the upper corners of a comparatively large sheet.

10 In accordance with a recognized method of hotel accounting, it is customary for a typist at the time of the registration of a guest to type his name and address, the number of the room to which he is assigned, 15 and the date in the upper left-hand corner of a statement-sheet which is kept in duplicate and on a set of small memorandum slips which are distributed among the various departments of the hotel.

20 An object of this invention is to provide means for relatively positioning the statement-sheets and the slips and for controlling the movements of the latter during the typing operation in a way to make possible the typing of all of them at a single operation. In addition to typing at the top of 25 the statement-sheets the data mentioned, it is also necessary to type the same or similar information on detachable stubs at the lower extremities of said sheets, and this is done, according to the present invention, 30 immediately after the typing at the top of the statement-sheets and without removing the statement-sheets from the machine.

35 A feature of the invention is the provision, in a machine for the purpose set forth, of a front-insertion guide-sheet of sufficient flexibility to be passed about the platen, but which is stiff enough to press firmly 40 against the lower margin of the pack of memorandum slips and draw the slips rearward into the machine from the front thereof.

45 Another feature of the invention is the provision, in combination, of an aligning plate at the front of the machine, a front insertion guide-sheet of the character mentioned above, a gage on the aligning plate for positioning the front-insertion guide-

sheet, and means for pressing the front-insertion guide-sheet toward the platen. 55

Another feature of the invention is the provision, in a machine having a front-insertion guide-sheet of the character set forth, of means for holding the guide-sheet stationary while the feed-rollers are cast off to permit the shifting of the statement-sheets relatively to the guide-sheet preparatory to writing on the stubs at the bottom of the statement-sheets. 60

65 Other features and advantages will hereinafter appear.

In the accompanying drawings,

70 Figure 1 is a front elevation of a part of a typewriter having the present improvements applied thereto.

75 Figure 2 shows a statement-sheet with a pack of the memorandum slips in the relative positions occupied by them during writing.

80 Figure 3 shows the statement-sheet and memorandum slips positioned with reference to an aligning plate at the front of the machine.

85 Figure 4 is a vertical sectional view taken on the line 4-4 of Figure 1, showing the sheets in the positions to which they are adjusted by the aligning plate.

90 Figure 5 is a view similar to Figure 4, showing the sheets in the positions occupied by them during the writing of the first line.

95 The typewriting machine comprises a platen-frame 10, a rotary platen 11 mounted therein, the usual line-spacing mechanism 12 for advancing the platen step by step to bring successive portions of the work into position to be written upon by types 13, feed-rollers 14 co-operating with the platen, and means for releasing the feed-rollers including the usual feed-roller releasing handle 15.

100 A sheet 16 of thin flexible material of substantially the same width as the platen, hereinafter referred to as the front-insertion guide-sheet, or simply as the guide-sheet, passes around the platen from the rear, and has its rear end supported upon the usual paper-shelf 17. This guide-sheet 16 may be made of paper or other suitable material having the required characteristics of resilience and flexibility.

105 Paper-fingers 18 pivoted on a rod 19 extending across the platen-frame carry rollers 20 which are spring-pressed toward the

- platen, for engaging the lateral margins of the guide-sheet 16. The springs 21 for pressing the rollers 20 toward the platen may advantageously be made stronger than usual 5 in order to prevent any sidewise slipping of the guide-sheet with relation to them.
- A paper-guiding chute 22 for guiding the statement-sheets to the platen is mounted on a rod 23 in the rear of the paper-shelf 17.
- 10 This chute may conveniently be like that disclosed in the patent to McLaughlin, No. 1,209,865, granted December 6, 1916, and need not therefore be described in detail. It will suffice here to say that the chute is pivoted on the rod 23 extending between brackets 24 at opposite sides of the platen-frame 10, and is urged in a clockwise direction, as seen in Figure 4, by a spring 25 whereby its lower extremity is pressed at all times into 15 engagement with the guide-sheet 16, and will be effective either alone or in co-operation with the rollers 20 to prevent disarrangement of said guide-sheet during movements of the statement-sheets 26 relatively thereto.
- 20 25 The machine is equipped with a rising sheet presser or guide 27, arranged to participate in the case-shifting movements of the platen-frame, similar to that disclosed in the patent to Helmond, No. 1,302,161, granted April 29, 1919. This guide is drawn to its lower limit of movement by springs 28 connected to it and to pins 29, which springs are also effective to swing it toward 30 the platen into pressing engagement therewith.
- An aligning plate 30 is mounted on a rod 31 extending between brackets 32 at the opposite ends of the platen-frame 10 in position to receive the statement-sheets 26 at the 35 delivery side of the platen. This aligning plate 30 is provided with an end gage 33 and a left-side gage 34 for gaging the ends and left edges, respectively, of the statement-sheets 26 and the memorandum slips 35, and with a right-side guide 36 for guiding the statement-sheets. The aligning plate 30 is also provided with end gages 37 at its opposite sides and outside the side gages 34 and 36 for engaging the leading edge of the 40 front-insertion guide-sheet 16 which is wider than the statement-sheets, to position it relatively to the statement-sheets 26 and memorandum slips 35 with its leading edge slightly above the lower edges of the memorandum slips. The upper left-hand corner of the aligning plate 30 is cut away, as indicated at 30*, to permit the slips and statement-sheets to be gripped by the operator in positioning them.
- 45 50 55 60 65 The machine is used for doing the work described in the following manner. The feed-rollers 14 are released; the front-insertion guide-sheet 16 is positioned with its leading edge in engagement with the gages 37 on the aligning plate 30; the statement-sheets 26 guided by the chute 22 are passed around the platen 11 from the back between the platen and the guide-sheet; and their leading edges are brought into engagement with the end gage 33 on the aligning plate. 70 The pack of memorandum slips 35 is then positioned by means of the gages 33 and 34 on the aligning plate, to overlie the statement-sheets, with its lower margin beneath the upper margin of the front-insertion guide-sheet 16 and with its upper and left-hand edges coinciding with the corresponding edges of the statement-sheets. The feed-rollers 14 are then thrown on and the platen is turned backward by a knob 38 to feed the statement-sheets and the pack of slips down to the first printing line, the guide-sheet 16 being also fed by the platen at the same time. The guide 27 co-operates with the rollers 20 to press the front-insertion guide-sheet 16 toward the platen during this movement and thus cause its upper margin to press firmly against the lower margin of the pack of slips. The required data is then typed on the slips and statement-sheets, the platen being line-spaced between lines in the usual way. After the slips have been typed, they may be removed from the machine, but it is still necessary to type the name and address of the guest, his room-number and the date on detachable stubs 39 at the bottom of the statement-sheets 26. 80 85 90 95 100 105 110 115 120 125 130
- In order to do this, the feed-rollers 14 are again released to enable the statement-sheets to be drawn forward without disturbing the guide-sheet 16. The lower extremity of the chute 22, pressing against the guide-sheet 16, prevents shifting thereof during this adjustment. In typing the particular forms for which the machine is designed, the leading edge of the guide-sheet 16 will be located a sufficient distance below the writing position at this stage to permit the first line of writing on the stubs 39 to be brought directly to, and exposed for typing in, said position and to permit a subsequent line-spacing movement of the platen at typing of the detachable stubs, the guide-sheet being advanced meanwhile, without bringing the guide-sheet to the writing position. If the guide-sheet is not so positioned, the statement-sheets 26 will be drawn forward by the operator sufficiently far to bring the second writing line into view, and the statement-sheets and guide-sheet will then be turned back in unison by the platen and the feed-rollers 14 to correctly locate the first writing line in writing position. With the feed-rollers on, the statement-sheets may be fed after the typing of the first line on the stubs to the second writing line thereof. All of the data is written on two lines of the stubs. After the writing of the second line, therefore, the statement-sheets may be removed from the machine and the guide-sheet may be repo-

sitioned with reference to the gages to prepare it for a subsequent operation.

Variations may be resorted to within the scope of the invention, and portions of the 5 improvements may be used without others.

Having thus described my invention, I claim:

1. In a typewriting machine for typing a brief inscription at one operation upon a 10 short slip and at the head of a long work-sheet, and for thereafter typing a brief inscription at the foot of the long work-sheet, all at a single insertion of the long work-sheet and the short slip in the machine; in combination, a revoluble platen, an aligning plate above the platen, at the front thereof, a leading-edge gage on the aligning plate for gaging the short slip and the long work-sheet by their leading edges to collate them, 15 a flexible sheet in the machine, outside the long work-sheet, forming a feeding gripper and front-insertion guide for the short slip, the flexible sheet-gripper and guide being wider than the long work-sheet and the short slip, leading-edge gages on the aligning plate, outside the bounds of the long work-sheet and the short slip, and considerably 20 below the first-mentioned leading-edge gage, for positioning the guide and gripper-sheet with its upper margin above the writing line and overlapping the lower margin of the 25 gaged short slip, but leaving the upper portion of said slip exposed for typing, feed-rolls 30 cooperating with the platen to feed the long work-sheet and the gripper-sheet backward, and causing them to draw the short slip down to writing position, the feed-rolls being releasable when the short slip has been typed, to permit the long work-sheet to be 35 advanced to position for typing at the foot thereof, while the guide and gripper sheet remains stationary below the writing line, and means for gripping the guide-sheet stationary 40 during such advance of the long work-sheet.

2. In a typewriting machine for typing a brief inscription at one operation upon a short slip and at the head of a long work-sheet, and for thereafter typing a brief inscription at the foot of the long work-sheet, all at a single insertion of the long work-sheet and the short slip in the machine; in combination, a revoluble platen, an aligning plate above the platen, at the front thereof, a leading-edge gage on the aligning plate for gaging the short slip and the long work-sheet by their leading edges to collate them, 50 a flexible sheet in the machine, outside the long work-sheet, forming a feeding gripper and front-insertion guide for the short slip, the flexible sheet-gripper and guide being wider than the long work-sheet and the short slip, leading-edge gages on the aligning plate, outside the bounds of the long work-sheet and the short slip, and considerably 55 below the first-mentioned leading-edge gage, for positioning the guide and gripper-sheet to overlap the lower margin of the gaged short slip, but to leave the upper portion of the slip exposed for typing, means for gripping the margins of the guide and gripper sheet to hold it stationary in its gaged position during adjustment of the long work-sheet and the short slip, feed-rolls co-operating with the platen for feeding the long work-sheet and the gripper-sheet backward, 60 and causing them to draw the short slip down to writing position, the feed-rolls being releasable when the short slip has been typed, to permit the long work-sheet to be advanced to position for typing at the foot thereof, while the guide and gripper sheet remains stationary below the writing line, and means for gripping the guide-sheet stationary 65 during such advance of the long work-sheet.

low the first-mentioned leading-edge gage for positioning the guide and gripper-sheet to overlap the lower margin of the gaged short slip, but to leave the upper portion of said slip for a space greater than the combined length of the two inscriptions exposed for typing, feed-rolls co-operating with the platen to feed the long work-sheet and the gripper-sheet backward, and causing them to draw the short slip down to writing position, means for pressing the short slip to the platen at and above the writing line to assist in controlling and feeding the short slip for typing, the feed-rolls being releasable when the short slip has been typed, to permit the long work-sheet to be advanced to position for typing at the foot thereof, while the guide and gripper sheet remains stationary below the writing line, and means for gripping the guide-sheet stationary during such advance of the long work-sheet.

3. In a typewriting machine for typing a brief inscription at one operation upon a short slip and at the head of a long work-sheet, and for thereafter typing a brief inscription at the foot of the long work-sheet, all at a single insertion of the long work-sheet and the short slip in the machine; in combination, a revoluble platen, an aligning plate above the platen, at the front thereof, a leading-edge gage on the aligning plate for gaging the short slip and the long work-sheet by their leading edges to collate them, a flexible sheet in the machine, outside the long work-sheet, forming a feeding gripper and front-insertion guide for the short slip, the flexible sheet-gripper and guide being wider than the long work-sheet and the short slip, leading-edge gages on the aligning plate, outside the bounds of the long work-sheet and the short slip, and considerably below the first-mentioned leading-edge gage for positioning the guide and gripper-sheet to overlap the lower margin of the gaged short slip, but to leave the upper portion of the slip exposed for typing, means for gripping the margins of the guide and gripper sheet to hold it stationary in its gaged position during adjustment of the long work-sheet and the short slip, feed-rolls co-operating with the platen for feeding the long work-sheet and the gripper-sheet backward, and causing them to draw the short slip down to writing position, the feed-rolls being releasable when the short slip has been typed, to permit the long work-sheet to be advanced to position for typing at the foot thereof, while the guide and gripper sheet remains stationary below the writing line, and means for gripping the guide-sheet stationary during such advance of the long work-sheet.

4. In a typewriting machine, a platen, feed-rollers co-operating therewith and movable to inoperative positions, a chute for

- guiding a long sheet to the platen from the rear, a front insertion guide-sheet arranged for guiding short sheets around the platen from the front thereof and participating in the line-feeding movements of the platen when the feed-rollers are in operative positions, a shelf at the rear of the platen beneath the chute supporting the guide-sheet, and means pressing the chute against the shelf for gripping the front insertion guide-sheet for preventing movement thereof when the feed-rollers are in inoperative positions, to permit the advance of the long work-sheet relatively to the guide-sheet.
5. In a typewriting machine for typing a brief inscription at one operation upon a short slip and at the head of a long work-sheet, and for thereafter typing a brief inscription at the foot of the long work-sheet, all at a single insertion of the long work-sheet and the short slip in the machine; in combination, a revoluble platen, a flexible sheet in the machine, outside the long work-sheet, forming a feeding gripper and front-insertion guide for the short slip, feed-rolls co-operating with the platen for feeding the long work-sheet and the gripper-sheet backward, and causing them to draw the short slip down to writing position, the feed-rolls being releasable when the short slip has been typed, to permit the long work-sheet to be advanced to position for typing at the foot thereof, while the guide and gripper sheet remains stationary below the writing line, and means for gripping the guide-sheet stationary during such advance of the long work-sheet.
6. In a typewriting machine, a platen, feed-rollers co-operating with the platen, a flexible gripper and guide sheet for short slips extending around the platen and arranged to participate in the rotation thereof, a gage at the delivery side of the platen for positioning long sheets and short slips with relation to each other, a gage for locating the short-slip guide with its upper margin above the writing line in position to cover the lower margins only of the gaged short slips, and means for pressing the short-slip guide and gripper to the platen by its side margins and at its middle at and above the writing line.

7. In a typewriting machine, a platen, a platen-frame, means at the delivery side of the platen for relatively positioning a long work-sheet and a short sheet slip, means for drawing the long work-sheet backward to position it for writing, and means comprising a sheet-presser mounted independently of the platen-frame but arranged for case-shifting movement therewith, and a guide and gripper sheet held to the platen by said sheet-presser, for causing the short slip to be drawn to writing position from above the writing line in unison with the long work-sheet.

8. In a typewriting machine, the combination with a revoluble platen, of a flexible front introducer sheet for the work feedable to and fro around the platen, means for gaging the advance of said introducer sheet at a work-introducing position with its leading edge a short distance above the writing line, feed-rolls for feeding the introducer sheet backward to draw the work to writing position in the machine, there being provision for the travel of the excess length of the introducer sheet at the rear of the platen, and means for gripping the introducer sheet and holding it stationary below the writing line during subsequent adjustment of the work in the machine.

9. In a typewriting machine, the combination with a revoluble platen, of a flexible front introducer sheet for the work feedable to and fro around the platen, a collating table at the front of the platen having gaging means for relatively positioning introduced work-sheets preparatory to feeding them to writing position, means for gaging the advance of said introducer sheet at a work-introducing position with its leading edge a short distance above the writing line and in predetermined co-operative relation to the work-sheets, feed-rolls for feeding the introducer sheet backward to draw the work to writing position in the machine, there being provision for the travel of the excess length of the introducer sheet at the rear of the platen, and means for gripping the introducer sheet and holding it stationary below the writing line during subsequent adjustment of the work in the machine.

JESSE A. B. SMITH.
